CONTINUOUS SOAP PROCESS

James K. Gunther, Hinsdale, Ill., assignor to
 Industrial Patents Corporation, Chicago, Ill., a
 corporation of Delaware

Application December 4, 1943, Serial No. 512,937

18 Claims. (Cl. 260—418)

1

The present invention relates to a continuous saponification process and more particularly to a process carried out in such a manner as to effect an improvement in the quality of the soap product and a maximum recovery of the glycerine which is formed as a result of the saponification reaction.

The manufacture of soap in a continuous saponification process has been proposed in the prior art. A prominent factor believed to be essential to the success of such a process, has been the employment of a sufficiently elevated temperature to render the soap in molten form when water and other vaporizable materials are removed therefrom, in order to maintain fluidity in the coils, and facilitate the substantially complete separation of glycerine from the molten material thus formed in a vapor-separating zone. The necessity of maintaining elevated temperatures during the reaction has resided primarily in the fact that the soap product must be maintained in a flowable condition, as it is formed, so that the process may be continuous in the saponification coil. The application of a sufficient amount of heat to liquefy the soap and liberate glycerine, however, is ordinarily destructive of the glycerine molecule, and results in the decomposition and consequent loss of a very large portion of this valuable by-product of the saponification reaction. Furthermore, the severe character of such conditions is found to be conducive to discoloration and general depreciation in quality of the soap product which it is desired to recover in the process.

It has also been proposed that continuous saponification of fatty material be effected with anhydrous caustic. The employment of anhydrous caustic has generally been considered essential in a continuous process in order to accelerate the reaction and avoid the necessity of separating water from the saponification products. The dehydrating action of anhydrous caustic, however, has been found to have a disastrous effect on the glycerine recovery from the saponification reaction, as noted from the combined yield of distilled glycerine and that contained in the soap product.

A further suggestion of the prior art is that continuous saponification be accomplished by the use of aqueous caustic soda. However, in carrying out such a process, it is inevitably necessary to employ such a high temperature of saponification in order to secure the necessary fluidity of the soap product, as well as to facilitate the separation of glycerine therefrom, that the yield of

2

glycerine is considerably impaired. Furthermore, the use of an aqueous caustic alkali has been restricted to highly concentrated solutions so as to avoid, in so far as possible, the large amounts of heat otherwise required to vaporize the water content of the saponification product.

The utilization of viscosity reducing agents has been proposed to lubricate the flow of the reaction products through the reaction zone. The amount of such diluents, however, has been too small to improve the glycerine recovery and the character of the soap product, since excessive temperatures must still be employed which are adequate to maintain the soap product in a fluid condition.

It is an object of the invention to provide a continuous process for making an improved anhydrous soap product.

Another important object of the invention is to provide a continuous process of saponification while effecting a substantial increase in the recovery of glycerine as a by-product.

Another object of the invention is to provide a continuous process in which saponification is accomplished in a considerably shorter time period and at a considerably lower temperature than possible by known processes.

Another important object of the invention is to provide for improved contact between the soap forming reactants subjected to saponifying conditions.

Another object is to provide a low temperature, continuous saponification providing the maximum glycerine recovery and improvement in the soap product.

Other objects and advantages, if not specifically pointed out, will be apparent to those skilled in the art from the following detailed description of what is considered to be the preferred embodiment of the invention.

The invention accordingly comprises the several steps in the relation of one or more of such steps with respect to each of the others thereof, which will be exemplified in the process hereinafter disclosed and the scope of the invention indicated in the claims.

The invention broadly contemplates the continuous saponification of saponifiable material with an aqueous solution of a saponifying reagent in the presence of a sufficient amount of an inert diluent to facilitate the saponification reaction at a temperature substantially below the melting point of the pure soap when anhydrous, while maintaining sufficient pressure in the reaction zone to avoid vaporization of the glycerine

and the diluent in sufficient amount to adversely affect the fluidity. It also contemplates saponification with sufficient inert diluent to facilitate the saponification reaction at a temperature below that which would render the pure soap molten after the volatile matter has been removed therefrom; that is, at temperatures above the melting point of the pure soap but below the minimum temperature which would render the pure soap molten when the volatile matter is flashed off. The diluent is preferably miscible with the saponifiable material and the soap product of the saponification reaction and the amount of diluent is preferably a major proportion of the saponifiable material. The presence of an adequate amount of inert diluent renders the soap product fluid at temperatures substantially below the melting point of the soap and the use of an aqueous caustic has been found to promote the saponification reaction even at this relatively low temperature. By maintaining a sufficient pressure on the reaction mixture to avoid substantial vaporization of the inert diluent, the fluidity thereof is preserved, although if a substantial excess of the inert diluent is employed, partial vaporization thereof may occur without affecting the fluidity of the mixture. At the saponification temperature, partial or complete vaporization of water may or may not occur, depending on the degree of pressure applied to the reaction mixture.

More particularly, the invention comprises a continuous saponification process with a relatively dilute aqueous caustic alkali solution of a concentration of about 50 per cent caustic or less by weight and in the presence of an inert diluent in an amount equal to at least a major proportion (over 50 per cent) of the saponifiable material and preferably at least about 75 per cent by weight or over based on the saponifiable material. The aqueous alkali solution, saponifiable material and inert diluent are preferably formed into an emulsion and subjected to saponifying conditions in a reaction zone of restricted cross section, while maintaining the fluid mixture under sufficient pressure to substantially prevent vaporization of the inert diluent and glycerine formed in the reaction. Sufficient sensible heat may then be advantageously supplied to the saponification products to vaporize the inert diluent and glycerine, and the mixture sprayed into a low pressure zone wherein the inert solvent and glycerine volatilize by partial pressure distillation and are continuously removed, leaving a comminuted soap product which is likewise continuously removed from the low pressure zone. It is preferred to operate in such a manner that the saponification reaction is substantially complete prior to supplying the required sensible heat for vaporization of the diluent and glycerine. The water may be substantially all vaporized by the time the products emerge from the final heating stage.

The diluent used in the process may be any substance which is substantially inert to the reactants and the products of saponification. It is preferred to employ an inert organic diluent which boils not greatly in excess of about 400° F. at the pressure in the low pressure zone and which is substantially immiscible with water and the glycerine formed in the reaction and substantially miscible with the soap. Solvents such as certain alcohols which are miscible with water and glycerine may be utilized provided they possess the other requisite physical properties.

The lower limit for the boiling point of a suitable inert diluent will be governed by the type of apparatus employed in the process and the ability thereof to stand elevated pressure at the saponification temperature. A preferred inert diluent for use in the process is a petroleum fraction known as "Skellysolve K" which has a boiling range of from 450° F. to 500° F. Other inert diluents which may be employed include kerosene, naphtha, gas oil, toluene, xylene and certain narrow cuts of known hydrocarbon fractions or various pure hydrocarbons which would possess the desired physical properties in relation to the particular saponifiable materials and saponification products which are formed. In some cases, non-inflammable type diluents, such as trichlorbenzene or tetrachlorethane, may be preferred. The saponifying reagent may consist of any material capable of converting an ester into an alcohol and an acid salt, such as caustic soda or caustic potash. Examples of suitable saponifiable materials include animal and vegetable fats and oils, such as tallow and coconut oil or any organic ester susceptible to saponification.

Figure 1 of the drawing illustrates diagrammatically a form of apparatus which can be employed for carrying out the process of the invention. Figure 2 is a detail of the homogenizing device shown generally in Figure 1.

Referring more particularly to Figure 1 of the drawing, 10 indicates a tank for holding a solution of saponifiable fat, for example, tallow, in an inert diluent which may be prepared at a station not shown and supplied to the tank through a conduit 11 and valve 12. Another tank indicated at 13 is provided for holding a solution of a saponifying reagent, for example, a caustic soda solution prepared in the proper concentration, and may be charged into the tank through the conduit 14 and valve 15. The solution of saponifiable fat and aqueous caustic soda in the proper concentrations are drawn through conduits 16 and 17, respectively, by proportioning pump 18 driven by a motor 19. The proportioning pump may be of the reciprocating piston type and is regulated to properly proportion the two streams in the correct ratio for saponification and to force the mixture through a homogenizing device. From the proportioning pump 18, the saponification reactants flow through a conduit 19 to a homogenizer 20, wherein an emulsion is formed comprising microscopic globules of caustic soda solution dispersed in the solution of saponifiable material. The emulsion may contain small amounts of soap formed by the instantaneous saponification of any free fatty acids contained in the fat, which function to stabilize the dispersion of the aqueous caustic soda phase in the inert solvent medium.

Where low quality fats containing high percentages of free fatty acids are used, it may be necessary to heat the solution of saponifiable fat stream prior to homogenization in order to insure fluidity after the free fatty acids have been saponified by the caustic. The temperature required will be determined by the amount of soap formed prior to passing the mixture through the saponification coil.

The homogenizing device shown in detail in Figure 2 comprises a valve 45 urged against a valve seat 46 by a heavy spring 47 mounted on the valve stem 48. The free end of the valve stem is carried by a stuffing box 49. In opera-

tion, the valve 45 is opened by the pressure of the mixture provided by the proportioning pump 18. In flowing through the homogenizer, the mixture is subjected to severe mechanical agitation by the shearing action of the heavily loaded valve. As a result, the pressure on the mixture may be reduced from 100 pounds per square inch to nearly atmospheric pressure. A suitable homogenizer may be any device capable of forming a homogeneous emulsion of the products to be saponified, for example, certain types of high speed mixing pumps have been found satisfactory.

From the homogenizer 20, the emulsion is passed through conduit 21 to a mixer 22 where any small differences in the ratio of reactants due to the reciprocating action of the proportioning pump are equalized by agitation. The mixer 22 may be provided with agitators 23 which are driven from any suitable source of power through a pulley 24. The homogeneous emulsion, possessing a high degree of fluidity, thereafter passes through conduit 25 and pump 26 to saponification coil 28 via conduit 27. The saponification coil may be provided with any suitable heating means, for example, a burner 29 or oil bath to raise the temperature of the emulsified mixture to that necessary for complete saponification. This temperature will vary inversely with the length of time the mixture remains in the coil, being about 400° F. for a 7-minute reaction period and lower for longer periods of residence in the coil. The temperature of saponification is preferably substantially below the melting point of the soap when anhydrous, which is approximately 482° F. The pressure maintained in the coil is approximately 100 pounds per square inch. As the reaction proceeds, the character of the mixture changes from an emulsion of fat-solvent solution and aqueous caustic soda to a highly fluid, gel-like phase of uniform consistency and substantially composed of a mixture of soap, water, inert solvent and glycerine. The entire mixture is in a highly fluid liquid phase. The fluid mixture passes from the saponification coil through conduit 30 and into a relatively short preheating coil 31, wherein the temperature of the reaction mixture may be increased to approximately 480° F. in order to supply sufficient sensible heat thereto to facilitate the instantaneous vaporization of the inert diluent and glycerine from the soap product in the flash chamber 35. The pressure may be maintained at about 100 pounds per square inch in this coil. The coil 31 may be heated by a burner 32 or oil bath.

The reaction mixture then passes through conduit 33 to a restricted nozzle 34, from which it is continuously sprayed into the flash chamber 35, which may be held at a relatively low pressure, preferably less than 40 millimeters of mercury absolute, to effect a substantially complete separation of water, glycerine and other volatiles from the soap product, where this is desired. It is preferred to employ a nozzle of the atomizing type to produce a spray or fine mist of the reaction mixture in the flash chamber. The flash chamber is provided with a jacket 36 through which a suitable heating medium is circulated, via conduits 37 and 38, to furnish enough heat to compensate for heat lost from the system by radiation, conduction and convection. It is preferred that the flash chamber be maintained at a temperature high enough to prevent condensation of the volatile products at

existing conditions. It is ordinarily not necessary, however, to supply heat to the flash chamber for vaporization, since sufficient heat for this purpose is preferably supplied to the reaction mixture in the preheating coil.

As the mixture enters the flash chamber through the spray nozzle, the volatile components, including inert diluent and glycerine, immediately flash off by partial pressure distillation, leaving solid soap particles which settle to the bottom of the chamber in the form of a fine powder. The temperature of the soap particles and the vapors is considerably lower than the temperature which the reaction mixture acquired in the preheater as a result of heat loss in the vaporization process. The conditions in the heating coils and flash chamber are preferably controlled so that the temperature of the soap and vapors after flashing is reduced to about 320° F. to 350° F., or to a temperature just above the boiling point of the highest boiling volatile constituent at the existing conditions. The loss of heat occasioned by vaporization of volatiles insures the solid condition of the soap in the chamber. The low temperature of the soap contributes materially to the formation of a product of high quality. The soap particles as they settle to the bottom of chamber 35 are continuously removed by a conveyor 40. Any suitable type conveyor may be employed for continuously removing the soap while preserving the vacuum in the flash chamber; for example, a screw and shell arrangement, which compacts the soap particles as they are advanced by the screw conveyor, has been found satisfactory. The vapors separated from the solid soap particles by the flashing operation are continuously withdrawn through conduit 39 to a condenser 41. The condensate collects in a receiver 42 and uncondensed vapors may be passed if necessary through conduit 43 to a secondary condensing system, not shown, to complete the recovery process. A relatively high degree of vacuum is preferably maintained in the flash chamber and condensing system by a pump 44, thus facilitating the continuous withdrawal of volatiles from the flash chamber. The inert diluent is separated from the glycerine and water, refined and re-employed in the process. The glycerine is purified by distillation from the water content by means not shown. The glycerine recovered in the process is found to amount to nearly 100 per cent of the theoretical yield.

The above description is given for the production of a tallow soap for purposes of illustration only. It is to be understood that the specific conditions indicated are purely illustrative, may be varied within relatively broad limits and, in practice, will actually be governed by the particular results desired and the character of the reactants employed.

The amount of inert diluent employed is at least sufficient to render the reaction mixture flowable below a temperature at which the soap would be molten when the volatile matter is removed therefrom. Since the removal of volatile matter causes reduction in the temperature of the soap, the temperature of saponification may, in some cases, be slightly above the melting point of the pure soap but low enough to cause the formation of solid soap when such volatile matter is removed. It is preferred, however, to carry out saponification at a temperature substantially below the melting point of the pure soap in order to improve the quality of the soap product. The presence of an adequate amount of inert diluent

enables the saponification reaction to be carried out below temperatures at which the reaction mixture would, in the absence of the diluent, be too viscous to handle in a continuous process. It is to be observed that the soap content progressively increases as the reaction mixture progresses through the reaction zone and, therefore, the specific amount of diluent required should ordinarily be calculated on the basis of the expected soap yield. The inert diluent apparently functions as a solvent for the saponifiable material and the soap product and, after saponification has occurred, the reaction mixture has the appearance of a highly fluid sol. The specific amount of diluent in any case will be determined by the temperature and pressure conditions maintained in the process as well as the physical characteristics of the soap product which is produced.

In accomplishing saponification in the presence of a hydrocarbon type solvent, it is ordinarily desirable to employ an amount of solvent equivalent to at least 50 to 75 per cent and preferably from 100 per cent to 150 per cent by weight of the saponifiable material to provide a highly fluid reaction mixture as formation of the soap product occurs. It has been found that saponification may be effectively completed at temperatures of from 350° F. to 400° F. in an 80 foot coil of one quarter inch cross section with the employment of diluent concentrations indicated above. It has also been noted, however, that saponification may be effected at temperatures of from about 300° F. to 350° F. or even lower when a longer saponification coil is utilized.

It has been found in accordance with the invention that unexpected advantages result from carrying out saponification with an aqueous caustic solution in the presence of an inert diluent in the proportions indicated above. For example, the presence of moisture facilitates carrying the saponification reaction out at considerably lower temperatures than possible under analogous conditions employing an anhydrous type caustic. Also, a remarkable and unexpected increase in yield of glycerine from the saponification reaction is obtained. The latter particularly is believed to be due to the combination of the relatively low temperatures employed and the presence of moisture during the saponification reaction.

Although aqueous caustic solutions of substantially any degree of concentration may be employed, it has been found that best results, particularly from the standpoint of glycerine recovery, are obtained with solutions containing caustic alkali in concentrations of about 50 per cent or less by weight. In these ranges, it is possible to recover nearly 100 per cent of the glycerine yield from the reaction product. The minimum concentration of caustic in aqueous solution is ordinarily determined by considerations relevant to the removal of water from the saponification mixture. On the other hand, at least sufficient moisture is employed to dissolve the saponifying reagent at ordinary temperatures, although more concentrated solutions are possible with the use of heat. It is usually undesirable to employ aqueous caustic solutions more dilute than about 25 per cent of caustic alkali by weight.

An important factor serving to accelerate the saponification reaction at the relatively low temperatures resides in emulsifying the products to be saponified by passing them through an homogenizing device. Using aqueous caustic soda, fat

and an inert diluent and emulsifying the mixture, it has been found that the actual time period necessary to complete the saponification reaction may be reduced to about one sixth of that required for saponifying a similar hydrocarbon-fat mixture with anhydrous caustic and without emulsification. In this way, the productive capacity of a given plant may be greatly increased. The saponification reaction may, if desired be accomplished without emulsifying the reactants, in which event, the homogenizer is omitted and the mixture in the proper proportions passed directly to the saponification coil. When the homogenizer is omitted, however, longer reaction periods are required. As a general rule, the use of an emulsifying device has been found extremely advantageous in producing high quality soaps and increasing the by-product recovery.

In order to avoid the substantial vaporization of solvent and glycerine from the reaction mixture, the pressure thereon is preferably maintained substantially constant during flow through the reaction and heating zones and this may be accomplished by means of the pressure pump 26 and by the throttling action of the spray nozzle 34. It is preferred, moreover, that the cross sectional area of the conduit from the pump 26 to the nozzle 34 does not vary greatly, so as to provide means for unrestricted flow of the reaction mixture between these two points. It is also preferred that the conduit be of sufficient size so that the frictional resistance developed by the flow of the reaction mixture therethrough is negligible. It will be apparent that by these means vaporization of the diluent or solvent in sufficient amount to adversely affect fluidity of the mixture is avoided and the presence of a sufficient amount of inert diluent to render the soap product fluid is assured. Some vaporization of the volatile materials may occur or may even be desirable prior to discharge thereof into the flash chamber. However, the pressure is always regulated to insure the presence of an adequate amount of inert diluent in liquid phase to provide for the fluidity of the reaction mixture at temperatures below the melting point of the soap product. In practice, it has been found that an inert diluent of the hydrocarbon type in the proportions indicated above provides adequate fluidity for most fats at temperatures substantially below the melting point of the soap product. As pointed out hereinbefore, however, the specific amount of inert solvent required to achieve this condition will depend upon the conditions employed in a particular instance.

The primary function of the preheating coil is to supply the reaction mixture with a sufficient amount of sensible heat to provide for the substantially instantaneous and complete vaporization of vaporizable materials, including glycerine and volatile diluent from the soap product as it is sprayed into the low pressure zone. In the preheating coil, the reaction mixture is preferably raised momentarily to a temperature at which the water is substantially completely vaporized and at which the other vaporizable constituents will be vaporized when discharged through the spray nozzle. The temperature required for this purpose may be about 460° F. to 470° F. for a tallow saponification product using a caustic solution of about 25 per cent to 50 per cent caustic by weight. The temperature in every case will vary depending upon each specific set of operating conditions. The temperature to which the reaction mixture is raised in the preheating coil may,

in some cases, be above the melting point of the soap product but owing to the fact that this condition is only attained momentarily, the glycerine recovery and quality of the soap are unaffected. In any event, temperatures high enough at the existing pressure to vaporize glycerine are to be avoided. As a general rule, the preheating coil is less than one sixteenth of the length of the saponification coil and, therefore, the residence of the reaction mixture in the preheating coil is correspondingly abbreviated. The heat supplied to the reaction mixture in the preheating coil may be sufficient to accomplish the vaporization of water, but insufficient to cause substantial vaporization of the inert diluent or glycerine at the existing pressure. An adequate amount of heat to substantially vaporize the water content may be supplied without further elevation of the temperature, whereas a very substantial elevation in temperature would be required to furnish sufficient sensible heat to provide for the vaporization of water in addition to inert diluent, glycerine and other volatile matter in the flash chamber. In this way, it is possible to further conserve the glycerine recovery and avoid deterioration of the soap product.

In some cases, particularly where it is desired to produce a soap product having a high glycerine content or where glycerine recovery is not material, the preheating coil may be eliminated. In the latter case the reaction mixture passes directly from the saponification coil and through the spray nozzle into the flash chamber. In such cases, a more volatile diluent is preferably employed to reduce the sensible heat required for vaporization thereof in the flash chamber. The preheating coil, however, is preferred when it is desired to effect the substantial elimination of glycerine and other volatiles from the soap product in the flash chamber and avoid the use of high temperatures in the saponification coil, which, as pointed out above, have an adverse effect on the quality of the soap product and yield of glycerine.

Example 1

As an illustration of the invention, as applied to the production of tallow soap, 100 parts of a prime grade of tallow were dissolved in 114 parts of a diluent consisting of "Skellysolve K." The solution was continuously homogenized with a 51.1 per cent caustic alkali solution in the proportion of 12.91 parts of caustic solution to 100 parts of the fat-diluent solution. The resulting homogeneous emulsion was continuously passed through a saponification coil under a pressure of 100 pounds per square inch wherein the reaction proceeded at a temperature of about 400° F. The saponification reaction was completed in this coil. The reaction mixture was passed through a preheating coil at the same pressure where it attained a temperature of about 480° F. and thereafter was sprayed through a restricted nozzle into the flash chamber, wherein a pressure of about 12 mm. of mercury absolute was maintained. The pressure in the saponifying and preheating coils was maintained at approximately 100 pounds per square inch by means of the pressure pump. The time of flow for the reaction mixture through the saponification coil was about 7 minutes whereas the length of residence in the preheating coil amounted to about 25 seconds. The temperature of the flash chamber was maintained at approximately 400° F. The solid soap in the form of a

fine white powder dropped to the bottom of the chamber and was continuously removed without disturbing the vacuum therein. The vapors which separated by partial pressure distillation were continuously removed from the top of the chamber, the glycerine and diluent condensed in one condenser and the water vapor condensed in a secondary condensing system. The diluent was separated from the glycerine by stratification and returned to the system. The glycerine recovery was found to amount to 96.6 of the theoretical yield. An analysis of the powdered soap product showed that it contained 0.31 per cent glycerine or 3.2 per cent of the theoretical yield. The total percentage of glycerine accounted for amounted to 99.8 per cent of the theoretical yield.

Example 2

20 As a further illustration, 100 parts of tallow were dissolved in 115 parts of "Skellysolve K." This mixture was homogenized with 12.8 parts of a 50.6 per cent caustic soda solution to 100 parts of fat-diluent solution. The resulting emulsion was saponified at a temperature of 390° F. and pressure of 100 pounds per square inch. The reaction mixture was passed through a preheating coil at a temperature of 450° F. and pressure of 100 pounds per square inch and sprayed into a flash chamber maintained at a pressure of about 10 mm. of mercury. The temperature of the flash chamber was about 338° F. The volatile matter flashed off and was withdrawn from the chamber. The soap precipitated to the bottom of the chamber in the form of a very fine white powder. The glycerine recovery amounted to about 95 per cent of the theoretical yield. The powdered soap produced was of good quality and capable of being directly molded into milled bar soap without further purification.

40 The lower temperatures which were employed in the last example resulted in an improvement in the quality of the soap over the preceding example.

45 In the process of the present invention, an outstanding improvement in the character of the soap is obtained over that possible in following prior procedures. At the high temperatures ordinarily necessary to effect the complete removal of glycerine from a molten or plastic soap, the product is found to have a dark brown color as distinguished from soaps made from fats of similar grade by the conventional procedure. In contrast, soap made directly by the present process without further purification is comparable to that made by conventional boiling processes and suitable without further treatment for the manufacture of fine grade soaps. A particular noteworthy feature of the process resides in the low 55 temperatures of saponification which may be employed. It is thus possible to promote the saponification reaction at temperatures at least 40° F. or 50° F. below the lowest temperatures possible using anhydrous caustic. Furthermore, the actual 60 saponification period is about 10 minutes as compared to about 1 hour when using anhydrous caustic under comparable conditions in an ordinary continuous saponification process. It is, therefore, apparent that great savings are effected in equipment as well as a substantial increase in productive capacity.

70 Obviously many modifications and variations of the invention, as hereinbefore set forth, may be made without departing from the spirit and scope thereof, and therefore only such limitations

should be imposed as are indicated in the appended claims.

I claim:

1. In a process for the manufacture of soap, the step which comprises reacting a saponifiable material with an aqueous solution of a saponifying reagent in the presence of a relatively large amount of inert organic diluent having solvent properties for the saponifiable material, the amount of water in said aqueous solution being insufficient to precipitate the soap and said inert diluent being present in a sufficient amount to render the reaction mixture flowable and to enable the saponification reaction to be carried out below a temperature at which the soap would be molten when the volatile matter is removed.

2. In a continuous process for the manufacture of soap, the steps which comprise subjecting a mixture of a saponifiable material, an aqueous solution of a saponifying reagent and an inert organic diluent having solvent properties for the saponifiable material in an amount equal to at least 50 per cent by weight of a saponifiable material to saponifying conditions of temperature and superatmospheric pressure, the amount of water in said aqueous solution being insufficient to precipitate the soap, and separating the diluent under a reduced pressure whereby a soap of improved quality is produced.

3. In a continuous process for the manufacture of soap, the step which comprises subjecting a mixture of a saponifiable material, an aqueous solution of a saponifying reagent no stronger than about 50 per cent by weight of the saponifying reagent and an inert organic diluent having solvent properties for the saponifiable material in an amount equal to at least 75 per cent by weight of the saponifiable material to saponifying conditions of temperature and superatmospheric pressure, the amount of water in said aqueous solution being insufficient to precipitate the soap, whereby a soap of improved quality is produced.

4. In a process for the saponification of saponifiable material, the steps which comprise subjecting a fatty material and an aqueous solution of caustic alkali in the presence of a volatile hydrocarbon solvent for the fatty material to saponifying temperatures whereby soap and glycerine are formed, the amount of said hydrocarbon being sufficient to render the mixture flowable at a temperature below the melting point of the soap when the volatile matter therein has been removed and to facilitate the saponification reaction at said last mentioned temperature and the amount of water in the aqueous solution being insufficient to precipitate the soap, and providing sufficient pressure during the saponification operation to maintain the hydrocarbon in the liquid phase and to prevent vaporization of the hydrocarbon to the extent that the fluidity of the reaction products would be adversely affected.

5. A process substantially as described in claim 4 in which the hydrocarbon is a petroleum fraction having a boiling range of from about 400° F. to 500° F.

6. A process substantially as described in claim 4 in which the saponifying temperatures are within the range of about 300° F. to 470° F.

7. A continuous process for the manufacture of soap, which comprises subjecting a mixture of fatty material, an aqueous solution of a saponifying alkali and a hydrocarbon solvent for the fatty material to a saponifying operation at elevated temperature and under pressure sufficient

to maintain the hydrocarbon substantially in the liquid phase, the amount of hydrocarbon being sufficient to render the reaction mixture fluid below the melting point of the soap when the volatile matter therein has been removed and the water in said aqueous solution being insufficient to precipitate the soap in the mixture, providing sufficient heat in said saponifying operation to substantially convert said fatty material into soap and glycerine and discharging the reaction products into a zone of lower pressure whereby the hydrocarbon and glycerine are flashed off and the soap is precipitated.

8. In a process for the manufacture of soap, the steps which comprise forming an emulsion of a saponifiable material, an inert organic diluent having solvent properties for the saponifiable material and an aqueous solution of a saponifying reagent, said diluent being present in an amount equal at least to a major proportion of the saponifiable material and in sufficient amount to render the mixture fluid below the melting point of the pure soap, the amount of water in said aqueous solution being insufficient to precipitate the soap, and subjecting said emulsion to saponifying conditions of temperature and superatmospheric pressure.

9. A continuous process for the manufacture of soap, which comprises forming an emulsion of a saponifiable material, an inert organic diluent having solvent properties for the saponifiable material and an aqueous solution of a saponifying reagent, the amount of water in said aqueous solution being insufficient to precipitate the soap and said inert diluent being present in amount equal to a large proportion of the saponifiable material and in sufficient amount to enable the saponification reaction to be conducted below the melting point of the pure soap product, subjecting said emulsion to saponifying conditions of temperature and pressure and passing the resulting product into a low pressure zone to vaporize volatile material by partial pressure distillation and form a comminuted soap product.

10. A continuous process for producing soap, which comprises forming an emulsion of a saponifiable material, an inert organic diluent having solvent properties for the saponifiable material in an amount equal to at least about 75 per cent of the saponifiable material and an aqueous solution of a saponifying reagent, the amount of water in said aqueous solution being insufficient to precipitate the soap, subjecting said emulsion to saponifying conditions of temperature and pressure to form soap and glycerine, furnishing additional heat to the reaction mixture to vaporize the glycerine and diluent and passing said mixture into a low pressure zone to vaporize the glycerine and diluent by partial pressure distillation and to form a comminuted soap product.

11. A continuous process for the manufacture of soap, which comprises passing an emulsion of saponifiable material, a hydrocarbon diluent in an amount equal to at least about 75 per cent of the saponifiable material and an aqueous solution of saponifying agent through an elongated reaction zone of restricted cross section, the amount of water in said aqueous solution being insufficient to precipitate the soap, subjecting said mixture to saponifying conditions of temperature and superatmospheric pressure in said zone and then separating the soap and diluent from the reaction products.

12. A continuous process for producing soap,

13

which comprises passing a saponifiable material, a major proportion of an organic diluent having solvent properties for the saponifiable material and an aqueous solution of a saponifying reagent at saponifying conditions of temperature and pressure through a reaction zone of restricted cross section to form a reaction mixture including soap and glycerine, the amount of inert diluent being sufficient to render the reaction mixture flowable at a temperature below the melting point of the pure soap, maintaining a sufficient pressure in said zone to substantially prevent vaporization of the glycerine and inert diluent and discharging the mixture in finely divided form into a low pressure zone wherein glycerine and inert diluent are flashed off by partial pressure distillation to form a comminuted soap product.

13. A continuous process for the manufacture of soap, which comprises forming an emulsion of a saponifiable material, an aqueous solution of a saponifying reagent and an inert organic diluent having solvent properties for the saponifiable material in sufficient amount to retain the saponification mixture in a fluid condition below the melting point of the soap product, subjecting said emulsion to saponifying conditions of temperature and pressure to form soap and glycerine, further heating the reaction mixture to furnish sufficient heat to vaporize said glycerine and diluent at subatmospheric pressure while maintaining a superatmospheric pressure thereon to prevent vaporization of said glycerine and diluent and passing the reaction mixture into a zone of subatmospheric pressure to vaporize the glycerine and diluent by partial pressure distillation and to form a comminuted soap product.

14. A process for the manufacture of soap, which comprises heating a mixture of a saponifiable material, an aqueous solution of a saponifying reagent and a relatively large amount of an inert organic diluent having solvent properties for the saponifiable material to a saponifying temperature for a sufficient period to substantially complete the saponification of said saponifiable material, thereafter heating the mixture under pressure to a higher temperature for a relatively shorter time period to vaporize a substantial amount of the water and then reducing the pressure on the mixture whereby vaporization of remaining volatile substances occurs.

15. A process for the manufacture of soap, which comprises heating a mixture of a saponifiable material, at least about 75 per cent by weight based on the saponifiable material of an inert organic diluent having solvent properties for the saponifiable material and an aqueous solution of a saponifying reagent, in a primary heating zone to a saponifying temperature below the melting point of the pure soap product and for a sufficient period of time to substantially complete the saponification and to form soap and glycerine, thereafter heating the mixture under pressure in a secondary heating zone to a higher temperature for a relatively shorter time period to substantially vaporize the water and to furnish sufficient sensible heat to vaporize said inert diluent and glycerine when the pressure is reduced, then reducing the pressure on the mixture whereby

14

substantial vaporization of said inert diluent and glycerine occurs to form a comminuted soap product.

16. A process for the manufacture of soap, which comprises subjecting a mixture of a saponifiable material, an inert organic diluent having solvent properties for the saponifiable material in an amount at least equal to that of the saponifiable material and an aqueous solution of a saponifying reagent under pressure to a plurality of stages of heating, maintaining a temperature in an initial stage sufficiently high to substantially complete the saponification and to form soap and glycerine, maintaining a higher temperature in a final stage to supply sufficient heat to substantially vaporize the water and to furnish sufficient sensible heat to vaporize said inert diluent and glycerine when the pressure is reduced and then reducing the pressure on the mixture whereby substantial vaporization of said inert diluent and glycerine occurs to form a comminuted soap product.

17. A process for the manufacture of soap, which comprises forming an emulsion of a saponifiable material, an inert organic diluent having solvent properties for the saponifiable material in an amount at least equal to that of the saponifiable material and an aqueous solution of a saponifying reagent, subjecting said emulsion to a temperature below the melting point of the pure soap when anhydrous, to substantially complete saponification and form soap and glycerine, thereafter heating the mixture to a higher temperature to furnish sufficient sensible heat to vaporize said inert diluent and glycerine when the pressure is reduced and to substantially vaporize the water content of the mixture at the prevailing pressure, maintaining a sufficient pressure during the operation to avoid substantial vaporization of the glycerine and inert diluent and then reducing the pressure on the mixture whereby substantial vaporization of said inert diluent and glycerine occurs to form a comminuted soap product.

18. A continuous process for the manufacture of soap, which comprises passing a mixture of saponifiable material, a hydrocarbon diluent in an amount equal to about 75 to 150 per cent of the saponifiable material and an aqueous caustic alkali under pressure through an elongated heating and saponification zone of restricted cross section, subjecting said mixture in the initial stage of said zone to temperatures sufficiently high to effect saponification, subjecting the mixture to a higher temperature in the final stages of said zone, correlating the temperature and time of heating in said final stage whereby the mixture is raised to a temperature at which the water is substantially vaporized at the prevailing pressure and at which sufficient sensible heat is supplied to the mixture to substantially vaporize the glycerine and the hydrocarbon when the pressure is reduced, discharging the mixture into a vaporizing zone of reduced pressure, and separating in said vaporizing zone water, glycerine and hydrocarbon from the soap.

JAMES K. GUNTHER.
